BEVERAGE COOLING AND DISPENSING EQUIPMENT

Jerse O. Matteson, Muskegon, Mich., and John Ehrenpreis, Clarence W. Brown, and Robert H. Guyton, Chicago, Ill., assignors to the Bruns-wick-Balke-Collender Company, Chicago, Ill., a corporation of Delaware

Application January 13, 1933, Serial No. 651,460

6 Claims. (Cl. 225—1)

This invention relates to improvements in beverage cooling and dispensing equipment and has for one of its principal objects the provision of a compact and unitary installation of this sort which shall, in conjunction with mechanical refrigeration and a source of compressed air, be available for the ready and efficient cooling, distribution and serving of beverages, both bottled and in bulk.

One of the important objects of this invention is to provide in a compact beverage cooling and dispensing apparatus, a plurality of inter-changeable sections, whereby the same may be used, as desired, for cooling and dispensing beverages in bulk or bottles or both, and which may also be used for merely the storage and pre-cooling of such beverages.

Another important object of the invention resides in the provision of a service bar for beverages or the like and which shall be of dimensions so as to be readily fitted under the ordinary counter used for dispensing such drinks, while at the same time all space on the top of the service bar itself is available for use, thereby allowing the installation of the maximum of equipment and the handling of a maximum volume in the minimum of space.

Still another object of the invention is to provide a service bar for dispensing beverages or the like wherein a desired temperature, within the equipment and of the contained beverage, is always maintained, whereby a highly satisfactory dispensing service results.

Another and still further important object of the invention is to provide means for dispensing beverages from barrels or kegs, whereby the barrels or kegs themselves are installed in a refrigerating compartment of minimum dimensions, while at the same time ample and convenient access is afforded to the top of the barrel for the installation of the usual delivery and pressure pipes.

Another important object of the invention resides in the improved type of float-valve control and associated delivery means for the refrigerant whereby a more satisfactory operation is assured.

Other and further important objects of the invention will be apparent from the disclosures in the accompanying drawings and following specification.

The invention, in a preferred form, is illustrated in the drawings and hereinafter more fully described.

In the drawings:

Figure 1 is an elevational view of the improved

beverage cooling and dispensing means of this invention, showing the same from the service end.

Figure 2 is a top plan view of the apparatus shown in Figure 1.

Figure 3 is a sectional view taken on the line 3—3 of Figure 1, looking in the direction indicated by the arrows.

Figure 4 is a detail sectional view of one of the compartments in the cooler, the same being shown as used for cooling bottled beverages.

Figure 5 is a detailed sectional view of one of the compartments used for cooling beverages in bulk or barrels.

Figure 6 is a sectional view showing particularly the apparatus used for cooling the beverages just prior to the dispensing operation.

Figure 7 is an enlarged detail sectional view of the improved liquid cooling equipment shown in Figure 6.

As shown in the drawings:

The reference numeral 10 indicates generally a cabinet in which the improved beverage cooling and dispensing equipment of this invention is housed, the same being provided at one end with an open compartment preferably covered by wire mesh or the like 12 for the free ingress of air thereto, this compartment being adapted to receive the usual compressor 14 used for refrigeration purposes and also a compressed air tank 16 and an air pump 18, all as shown diagrammatically in Figure 3.

The other compartments are provided with doors 20, 22 and 24, respectively, the doors 20 and 22 being adapted to close chambers for the reception of kegs or barrels of beverage, these kegs or barrels being indicated at 26.

The compartment closed by the door 24 is adapted for the reception of bottles of beverage or the like, as illustrated at 28 in Figure 4, this compartment being accessible from the top by means of a lid or the like 30.

The compartments which contain the barrels or kegs are also reached from the top, through suitable openings, these being normally closed by means of lids 32, which lids are preferably of a smaller size than the cover 30 for the bottle compartment.

Coils adapted to contain the refrigerant are provided leading from the compressor 14, the location and arrangement of these coils being best illustrated in Figure 3 and the same being indicated by means of the reference numerals 34 and 36. The reference numeral 34 indicates generally the main cooling pipes and the reference numeral 36 is applied to the set of auxiliary coils 110

applied to the underside of a metal plate 38 chiefly for cooling the bottles 28.

The coils 36 are soldered or otherwise fixed by means of an actual metallic contact to the lower 5 face of the plate 38 whereby suitable conduction of the required temperature results.

A drip pan 40 is provided beneath the plate 38 and the coils 36, this being provided with a suitable outlet pipe 42 or the like. A plurality 10 of orifices 44 is provided in the element joining the drip pipe 40 and the plate 38, whereby a suitable circulation of air through this space is assured.

Another drip plate or gutter 46 extends beneath 15 the coils 34, as best shown in this figure and also in Figures 5 and 6. In Figures 5 and 6, wherein is illustrated the compartments for holding barrels, a bumper 48 is provided beneath the gutter 46 so that the same will not be damaged upon the 20 placing of a barrel or keg in the compartment.

The usual air lines 50 lead from the air tank 16 (Figures 3 and 5) and are adapted to force 25 the liquids in the kegs 26 upwardly and outwardly through discharge pipes 52 which are placed therein through a bunghole in the top of the barrel. These pipes 52 and their associated connections are inserted into the barrels through the 30 openings in the top of the kegs, which openings are normally closed by the lids 32. By means of this construction a barrel of liquid can be placed in its compartment and the air and delivery pipes, with adequate connections, then inserted into the barrel through the opening in the 35 top of the cabinet 10; the method of installation of the pipes 52 and appurtenances being best shown by means of the dotted lines in Figure 5.

In this manner a considerable saving of space 40 results, as the distance between the top of the barrel 26 and the bottom of the cover of the cabinet 10 can be reduced to a minimum. A delivery pipe 54 leads from each of the barrel pipes 52, these pipes having valves 56 fitted therein (Figure 3) wherein delivery from either keg or barrel 45 can be made, as desired, to a common outlet pipe 58 and which pipe in turn delivers the beverage to the pre-cooler 60, as best shown in Figures 6 and 7.

Pipe 58 extends into a chamber 62 in the pre-cooler 60, extending almost to the top of this 50 chamber and terminating in a restricted opening 64, but having, however, a larger opening 66 at the base thereof adjacent the bottom of the cooler. Obviously beer or any beverage forced from the barrels or kegs 26 through the pipes 52—54—58 55 will eventually fill the chamber 62 and the cooler 60. The closed end of the pipe 58 with the restricted opening 64 is for the purpose of preventing bumping. Delivery from this cooling 60 chamber is accomplished by means of a pipe 68 which leads to dispensing faucets or the like 70.

Surrounding the chamber 62 is a space between 65 its walls and the cooler 60, which space is filled with refrigerant, which refrigerant also extends into a float chamber at the top of the cooler 60. This float chamber contains a float 72, as best 70 shown in Figure 7, which controls the intake of refrigerant through a pipe 74 by means of a needle valve 76. Gaseous refrigerant is withdrawn from the chamber by means of a pipe 78 which 75 leads to a thermostat control 80 through a pipe 82 delivering to the compressor 14. The float 72 is of the open bucket type whereby undesired mixing of refrigerant with lubricant is eliminated; and additionally, an auxiliary intake pipe for li-

uid refrigerant extends from the needle valve 76 downwardly, as best shown at 84, to a point of discharge inside one of the main refrigerant pipes or coils 86. In this manner the desired level of refrigerant is maintained in the cooling chamber 60 at all times; while the incoming liquid refrigerant is delivered directly to the main line thereby providing for more efficient operation. Another branch of the main line 86 is also connected to another face of the cooling chamber 60, as best shown in Figure 7.

Other features of the invention include the usual expansion valve 88, as shown in Figure 3. A sink is shown at 90 in Figure 2; glass-washing apparatus 92; a drain 94; and the usual other or desired appurtenances.

Additionally, there is inserted into the top of the cabinet 10 a series of openings 96, as best shown in Figures 2 and 4, which abut against the coils 34 and in which bottles of beverages to be cooled may be inserted for quick lowering of the temperature of the contents, and also for storage purposes so that cooled bottled beverages of different types than the bottles in the regular bottle compartment may be always available.

The various compartments are made interchangeable and also flexible so that units of various size may be conveniently built up, as, for example, two or more bottle compartments may be employed in a unit, and these compartments may subsequently be inter-changed as necessity arises or occasion demands.

It will be evident that herein is provided a service bar or fixture for cooling and dispensing 110 beverages which includes in a compact mechanical and efficient unit all of the necessary appurtenances for the satisfactory dispensing of such beverages; and, in addition, there is provided an improved method of refrigeration, both as regards 115 actual cooling of the contents and the control of the refrigerant itself.

We are aware that many changes may be made 120 and numerous details of construction varied throughout a wide range without departing from the principles of this invention, and we therefore do not purpose limiting the patent granted thereon otherwise than as necessitated by the prior art.

We claim as our invention—

1. A beverage cooling and dispensing apparatus comprising a plurality of interchangeable compartments for bottled and barreled beverages and a common refrigeration means therefor, said refrigeration means being contained in a separate 130 compartment associated with said first-named interchangeable compartments, said compartment for the refrigeration means also containing means for delivering a fluid under pressure to the barreled beverage, for delivery purposes, together with delivery faucets, and a beverage pre-cooling means inserted in the pipe lines from the barrels to said faucets, said beverage pre-cooling means including a double walled chamber, the inner chamber containing a beverage under pressure 135 and the outer chamber a refrigerant.

2. A beverage cooling and dispensing apparatus comprising a plurality of interchangeable compartments for bottled and barreled beverages and a common refrigeration means therefor, said refrigeration means being contained in a separate compartment associated with said first-named interchangeable compartments, said compartment for the refrigeration means also containing a compressor for delivering air under pressure to

the barreled beverage, for delivery purposes, together with delivery faucets, and a beverage pre-cooling means inserted in the pipe lines from the barrels to said faucets, said beverage pre-cooling	circulation of air between the shelf and the plate.
5 means including a chamber for containing a beverage under pressure and the refrigerant surrounding said chamber, said refrigerant being contained in an outer chamber, said last named chamber including a float control for the refrigerant for the entire system.	5. A beverage cooling and dispensing means comprising a compressor for delivering air under pressure to original beverage containers, pipe lines from the containers to a beverage pre-cooling chamber, said pipe lines terminating in cylindrical heads having a restricted opening in the top thereof and relatively large openings at the sides thereof adjacent the bottom, and delivery means from the pre-cooling chamber.
10 3. A beverage cooling and dispensing means, including a compartment for cooling bottled beverages, a bottle-supporting shelf in the compartment and refrigerating coils in the compartment, and auxiliary refrigerating coils beneath and forming a part of the bottle-supporting shelf, a compartment for receiving and cooling barreled beverages and mechanical means for both refrigerating the compartments and supplying air	80 6. A beverage cooling and dispensing means comprising a compressor for delivering air under pressure to original beverage containers, pipe lines from the containers to a beverage pre-cooling chamber, said pipe lines terminating in cylindrical heads having a restricted opening in the top thereof and relatively large openings at the sides thereof adjacent the bottom, and delivery means from the pre-cooling chamber, together with a refrigerant chamber surrounding said pre-cooling chamber, said refrigerant chamber adapted for the retention of refrigerant at a relatively low temperature and also serving as a float chamber for control of the liquid and gaseous refrigerant.
15 20 25 30	85 90 95 100
4. A beverage cooling and dispensing means, including a compartment for cooling bottled beverages, a bottle-supporting shelf in the compartment and refrigerating coils in the compartment, and auxiliary refrigerating coils beneath and forming a part of the bottle-supporting shelf, and a drip plate beneath the bottle cooling and supporting shelf, together with means for allowing	105
